UNITED STATES PATENT OFFICE.

MAE CARRINGTON-STRANG, OF CHICAGO, ILLINOIS.

ABDOMINAL SUPPORTER.

No. 898,093.

Specification of Letters Patent.

Patented Sept. 8, 1908.

Application filed June 18, 1907. Serial No. 379,651.

To all whom it may concern:

Be it known that I, MAE CARRINGTON-STRANG, a citizen of the United States, and resident of Chicago, Illinois, have invented 5 certain new and useful Improvements in Abdominal Supporters of which the following is a specification.

My invention relates to an improved abdominal supporter, the object of which is to 10 uplift the abdomen and force the spine to support same, also to provide a light, easy fitting supporter having sufficient flexibility to adapt it to the movements of the wearer.

In the drawings—Figure 1 is a side view of 15 a supporter embodying my invention, in place upon the wearer. Fig. 2 is a front plan view of a supporter embodying my invention. Fig. 3 is a back plan view of the same. Fig. 4 is an enlarged perspective view of a 20 portion of the flat tubular members employed in my invention.

My supporter comprises a flat back section 5, upon the outer face of which the member 6 is suitably stitched or otherwise secured and 25 being provided with buckles 7. The members 5 and 6 are made of any suitable inelastic material, and the member 6 is secured to the end of the elastic band 8. The band 8 is made of knitted elastic material and consists of the strips 9 and 10. The strip 9 is 30 cut away at the point indicated by the numeral 11 so as to fit closely to the downwardly disposed end of the strip 10; the place at the top of the strips 9 and 10 at the point where 35 they meet is filled with a triangular member 12.

Upon the back face of the supporter, the band 13 of inflexible material is secured and 40 stitched through the supporter to hold the meeting edges of the triangular member 12 and the strips 9 and 10 securely together.

The vertically disposed strips 14, 15, 16, 17 and 18 are secured to the back face of the supporter at the point and in the manner indicated in Fig. 3 of the drawings, and adapting 45 it to slightly concave form to fit the abdomen of the wearer. These strips 14 to 18, inclusive, extend from the lower margin of the supporter upwardly. Similar strips 19 and 20 are extended downwardly from the top 50 edge or margin of the supporter and upon its back surface, and substantially parallel with the vertically extending strips 14 and 16.

Upon the front face of the supporter, the 55 strip 21 is secured in location registering with the location of the strip 20 upon the back of

the supporter, but extending entirely across the face of the strip 9; and a corresponding strip 22 registering with the location of the strip 19 is secured across the outer face of the strip 10 transversely. From the non-elastic vertical strips 21 and 22 there is no give of the elastic because the elastic strips 9 and 10 are stitched firmly to the gusset 12 and also to each other, thus providing a firm support 60 over the median line of the abdomen, which is most important in all laparotomy operations. A vertical strip 23 is secured to the outer face of the supporter at its vertical median line registering with the strip 15 upon the back 65 face of the supporter. The outer end of the strip 10 terminates in the flat member 24 provided with straps 25 which are preferably made of light textile fabric, readily perforated by the tongues of the buckles 8, and 70 hence not provided with eyelets in the drawings.

As a further means of securing the supporter in place, I provide the bands 26 and 27 of flat tubular rubber as illustrated in Fig. 80 4. The strip 10 at a point near the member 24 is provided with the buckle 28 engaging with the strap 29 on the terminal of the tubular member 26; the other extremity of the member 26 terminating in the strap 30 engaging 85 with the buckle 31 secured to the front surface of the supporter near the strip 23. The tubular band 27 is similarly provided with the terminals 32 and 33 engaging with the buckles 34 and 35, respectively. 90

The desired concavity at the front of the supporter is secured by bringing the ends of the strip members 9 and 10 together in approximately triangular form, one being concave and the other convex at their point of juncture, the convex member being projected downwardly to form an expansion or lip 36 provided with a selvage 37, and this shape of the front of the supporter is made permanent by means of the various strips 13, 14, 100 15, 16, 17, 18, 19, 20, 21, and 22, to which reference has heretofore been made and the additional strips 38 and 39 upon the front face of the supporter register respectively with the location of the strips 14 and 16 upon 105 the back face of the supporter.

The abdominal supporter thus described and illustrated in the drawings may be made in various widths and lengths as required, is light, cool and flexible, but at the same time 110 of sufficient strength to properly perform the functions of a supporter.

Having fully described my invention, what I claim as new and desire to have secured to me by the grant of Letters Patent, is:

As a new article of manufacture, an abdominal supporter comprising two strips of elastic material having their meeting edges concaved and convexed, respectively, a triangular section inserted at the top of the supporter at the meeting of the said strips, the 10 strip having the convex edge being provided with a downward lip or extension, inelastic strips disposed upon the front and back surfaces of the supporter to adjust it to the ab-

domen of the wearer, suitable detachable fastening devices at the rear of the supporter, 15 and flat tubular elastic bands removably secured to the supporter and adapted to pass around the legs of the wearer, substantially as described.

In testimony whereof, I have signed my 20 name to this specification in presence of two subscribing witnesses.

MAE CARRINGTON-STRANG.
